FLANGE AND RAIL LUBRICATOR

William H. Foster and Ira L. Dudley,
Princeton, W. Va.

Application July 1, 1932, Serial No. 620,324

15 Claims. (Cl. 184—3)

This invention relates generally to the lubrication of railway tracks and particularly to a lubricating device which may be positioned to apply lubricant to the flanges of passing vehicle wheels so that the same may be subsequently deposited where needed, such for instance as on curves and other critical points in the track.

Many efforts have heretofore been made to provide a track lubricating device capable of satisfactory operation under the severe conditions of operation which exist. Although devices have heretofore been available which are with some degree of success capable of applying a light lubricant, such as oil, to the desired position on a railway track, such devices have not proved entirely satisfactory for the reason that generally speaking they are incapable of handling a heavy lubricant, such for instance as grease. Under the operating conditions encountered on many railroads light lubricants, such as oil, do not satisfactorily lubricate the track and those devices which are capable of applying only this type of lubricant are not satisfactory. It is among the objects of the present invention to provide a lubricating device for railway tracks which is capable not only of efficiently applying light lubricant, such as oil where desired, but is also highly efficient in the application of heavy lubricant, such as grease.

An object of the present invention generally stated is to provide a railway track lubricating device, the operating parts of which are so constructed and arranged as to be operated by impact with a passing vehicle part without hazard.

A further object of this invention is to provide a railway track lubricating device wherein the charge of lubricant ejected upon each stroke will be substantially uniform notwithstanding non-uniformity which may exist between successive operating impacts.

Another object of this invention is to provide a railway track lubricating device so constructed and arranged as to be capable of operation under adverse weather conditions and efficient and positive in operation.

A more specific object of this invention is to provide a railway track lubricating device wherein the parts actuated by passing vehicle parts are arranged to move in such manner as to reduce the derailment hazards.

Other objects will become apparent to those skilled in the art when the following description is read in connection with the accompanying drawing, in which:

Figure 1 is a plan view of a railway track sec-

tion having applied thereto a lubricating device constructed and arranged according to the present invention.

Figure 2 is a sectional view in end elevation showing the device of the present invention in operating position.

Figure 3 is a longitudinal sectional view of a pump employed in the apparatus of this invention.

Figure 4 is a sectional view showing a lubricant applying device constructed in accordance with the present invention applied to a rail.

Figure 5 is a detail view of a distributor plate employed in the lubricator of the present invention.

Figure 6 is an enlarged sectional view of a portion of Figure 4.

In accordance with the present invention, generally stated, means is disposed in such position as to be engaged by and receive impact from a passing vehicle part, for instance the flange of the ordinary vehicle wheel and the force of this impact is transmitted through suitable mechanism to operate the moving parts of the lubricator. More specifically in accordance with the present invention the operating device just referred to is so arranged as to be moved laterally upon impact with the passing vehicle part, for instance a wheel flange, whereby derailment hazards are substantially avoided in view of the relative impossibility of ballast particles or other foreign substance hindering such lateral movement. In view of the fact that some variation in operating stroke in such an operating device as that just referred to may be expected, since some lateral play is provided for between the wheel flanges and the side faces of the rail heads, under ordinary circumstances the lubricating device of the present invention is preferably provided with a pump so constructed and arranged that the charge of lubricant delivered upon successive strokes thereof remains uniform notwithstanding variations in the length of the stroke of the operating device.

A feature of particular importance in the present invention is the capability of the lubricator to handle a heavy lubricant, such as grease, as well as to handle light lubricants, and in order to better adapt the lubricator of the present invention to the handling of heavy lubricants, such as greases, means is provided to facilitate feeding the lubricant to the pump and further to prevent channelling or the forming of air passages which tend to occur in the handling of greases. This invention further contemplates the provision of a lubricant apply-

ing device adapted to periodically deposit a charge of lubricant on the flange side face of a rail head and to control the flow of lubricant from the pump. More specifically in accordance with the present invention such lubricant applying device is operated by impact with a passing vehicle part, such for instance as the flange of the vehicle wheel and in order to better adapt the device to withstand the severe shocks of such impacts and reduce the probability of derailments consequent to the obstruction of its movement, such lubricant applying device is preferably mounted so as to substantially follow the arc of a circle upon impact with a passing vehicle part. By this arrangement not only is the mechanical shock to the device readily absorbed, by the springs provided, but the downward movement thereof is resolved into lateral movement whereby the severe hazards so liable to occur in the operation of such devices as move up and down, as for instance the presence of a piece of ballast therebeneath, are avoided and operation of the device rendered positive and safe.

Referring now particularly to the drawing for an illustrative embodiment of the present invention a railway track comprising parallel rails 1 and 2 is shown and the rails are in accordance with the usual practice spiked or otherwise secured to ties 3. Mounted adjacent the rail 1 and on the flange side thereof is an operating member 4 which, in the embodiment illustrated, comprises a relative long strip of metal, for instance steel, having an intermediate portion of substantial length 5 extending parallel to the rail and normally positioned at a distance therefrom less than the thickness of the flange of an ordinary vehicle wheel. At each end of the intermediate portion 5 is a flared portion 6 extending away from the rail as shown so that at the extreme ends the device is spaced from the flange side face of the rail head a distance safely beyond the maximum displacement of the flange of the passing vehicle wheel from the rail. The extreme ends of the device may be suitably anchored as by brackets 7 to the ties or otherwise supported. If desired, suitable springs may be provided for imparting additional resilience to the operating device.

To the intermediate portion of the part 5 is attached a lever 8 which may be pivoted upon a suitable plate carried by ties or otherwise mounted as at 9. It will be understood that suitable ears or lugs may be secured to the device 4 to permit ready attachment of lever 8. The lower end of the lever 8 as shown in Figure 2 extends downwardly below pivot 9 and is there connected to a drag link 11 extending transversely of the track and preferably positioned between two ties as shown in Figure 1. The drag link 11 may extend beyond the ends of ties 3 and be connected to a crank 12 carried by shaft 13 and mounted in suitable bearings in the wall of reservoir 14. The reservoir 14 may be of any desired size and shape but when heavy lubricants, such as greases, are to be handled the same is preferably provided with a hopper bottom as shown. Carried by the shaft 13 and positioned for oscillation back and forth within the hopper bottom of reservoir 14 is a series of agitator blades 15. A suitable pump 16 may be provided to receive lubricant from the reservoir 14 and discharge the same therefrom. In the embodiment illustrated the pump 16 is shown as connected at the bottom of reservoir 14, but it will be understood that the same may be disposed

on the interior thereof or at any desired location. Suitable driving connections may be provided for transmitting the force from drag link 11 to pump 16, such for instance as a series of links and levers as illustrated. In the embodiment shown the drag link 11 extends beyond crank 12 and is pivotally attached, with sufficient play to permit operation, to a bell crank lever 17 mounted upon the side of reservoir 14. The bell crank lever 17 may be connected as by link 18 to a crank 19 secured to one end of a shaft 20 mounted in suitable bearings carried by reservoir 14. On the lower end of the shaft 20 may be secured a crank 21 the outer end of which may be pivotally connected to the plunger of pump 16. It will be understood that the mechanical connections just described are shown merely for the purposes of illustration and that any suitable mechanism may be employed for transmitting an operating force from member 4 to pump 16. The discharge end of pump 16 may be connected by a suitable pipe 22 to a lubricant applying device 23.

The lubricant applying device may be mounted upon a suitable base, for instance plate 24, which may be secured as by means of a clamp 25 to the flange of the rail 2. Mounted upon plate 24 on the opposite side of the rail from clamp 25 is a block 26 having a portion 27 formed to enter the recess between flange 28 of the rail 30 and head 29 thereof and preferably fitting up closely to the web of the rail. Block 26 may be provided with an arcuate guide surface 30 upon which may be seated a member 31 having a corresponding arcuate surface 32. Suitable means, as for instance a coil spring 33 seated in recess 34 of block 26 and suitably connected as at 35 to member 31 may be provided for maintaining member 31 in position upon block 26 and preferably biasing the same in an upward direction 40 as shown in Figure 4. A suitable cover 43 may be provided for enclosing the lower or inner extremity of member 31. As shown in the drawing the upper end of member 31 is disposed in the path of the wheel flanges which as they pass 45 over and engage the top of member 31 will operate to force the same downwardly and laterally against the action of spring 33. The top surface of member 31 may be suitably inclined as at 36 to facilitate climbing of the wheel flange 50 thereon and reduce the shock of the impact.

Carried in a recess 37 near the top of member 31 is a distributor plate 38 which in case it is intended to handle heavy lubricants may be formed of metal while in the case of light lubricants and oils may be formed of a piece of felt or other absorbent material. In the normal position shown in Figure 4 a part of the surface of distributor plate 38 lies in contact with flange side face 39 of rail 2 being biased thereagainst 55 by spring 39. In that portion of the surface of distributor plate 38 which normally contacts flange side face 39 of the head rail 2 a plurality of lubricant distributing grooves 49 are preferably provided as illustrated in Figure 5. Distributor plate 38 may be suitably retained in position as by means of a pivot pin 138 extending therethrough.

Pipe 22 leading from pump 16 may terminate in the form of a lubricant conduit 41 on the 70 interior of block 26. As clearly shown in Figure 4 lubricant conduit 41 may extend into a position adjacent the head of rail 2 and just beneath the flange side face 39 thereof. When in normal position shown in Figure 4, however, grooves 40 75

are preferably disposed beyond mouth 42 of the conduit 41 so as to be out of communication therewith, while the lower edge of distributor plate 38 may be disposed in such position as to block or close mouth 42 of lubricant conduit 41. If desired, the lubricant may be delivered otherwise, as for instance through the member 31 to which pipe 22 may be suitably connected. It will be understood, of course, that suitable gaskets may be provided in and around the mouth 42 of the lubricant conduit 41 to prevent leakage when the parts are in the normal position shown.

As pointed out hereinbefore the distance which operating member 4 is moved laterally upon impact with successive vehicle wheels is non-uniform, but it is apparent that the charge of lubricant delivered to the lubricant applying device 23 should be as nearly uniform as possible, and accordingly this invention contemplates a lubricant pumping means so constructed and arranged that the discharge thereof will be substantially uniform notwithstanding a non-uniformity of actual operating stroke. Referring now particularly to Figure 3 for an illustrating embodiment, such a pump may comprise a cylinder 44 having an inlet port 45 in communication with lubricant reservoir 14 and disposed to conduct lubricant from the reservoir to the interior of pump cylinder 44 when the parts are in the position shown. A plunger 46 is provided for operating on the interior of cylinder 44 and is provided with a shank 47 connected to receive its driving force through crank 21 or other suitable operating mechanism. At the end of cylinder 44 is an outlet 48 in which is seated a suitable ball valve 49 normally maintained in seating position as by spring 51 and arranged to discharge into pipe 22. Plunger 46 may be provided with an axially extending bore 52 terminating in a plurality of ports 53 arranged in spaced relation about the periphery of plunger 46. The position of ports 53 may be determined in accordance with the quantity of charge desired upon each operation of the plunger, it being understood that the more remote ports 53 are from the end 54 of the plunger the greater will be the charge of lubricant emitted on each operation of the pump. It will be apparent that bore 52 in conjunction with ports 53 operates as a by-pass whereby to regulate and maintain uniform the amount of lubricant discharged throughout outlet port 48 upon each operation of the plunger. It is evident that when ports 53 come into alignment with inlet port 45 the pressure upon that quantity of lubricant which is confined ahead of the plunger or between end 54 thereof and outlet port 48 will be released. Upon further operation of the plunger beyond this position, such lubricant as confined beyond the end of the plunger will find exit through bore 52, ports 53 and 45 back into the reservoir 14, it being understood that the force exerted upon valve 49 exceeds the pressure of the static column of lubricant in reservoir 14. It is apparent that suitable means may be provided for varying the position of ports 53 with reference to the end 54 of the plunger in order to vary the charge of lubricant delivered by the pump at will.

From the foregoing description the cycle of operations of the lubricator hereinbefore described will be understood to be as follows: upon approach of a railway vehicle the wheel flanges on one side thereof will be guided between flared portions 6 of member 4 and the flange side face of the head of rail 1. As movement of the vehicle continues the flared portions 6 operate to effect a camming

movement of member 4 moving the parallel portions thereof outwardly away from the rail until the parts assume the position shown in Figure 2. This lateral movement of member 5 effects a rotation of lever 8 in a clockwise direction about its pivot 9 and draws drag link 11 to the left as shown in Figure 2. As drag link 11 moves to the left agitator shaft 13 is oscillated and agitator blades 15 on the interior of reservoir 14 wipe or smear the lubricant contained therein back and forth in order to prevent channelling due to suction of pump 16 which is concurrently operated. The movement of drag link 11 toward the left is transmitted through the mechanism shown to move plunger 46 of pump 16 toward the left. No lubricant is, however, discharged by pump 46 until end 54 thereof moves into such position that port 45 is completely closed. Furthermore movement of plunger 46 is effective to discharge lubricant through port 48 and this continues until port 45 is again opened by coming into alignment with one of ports 53. Although the plunger 46 may actually move beyond this position it is understood that the active operation of the plunger pump ceases when port 53 opens port 45.

Pump 45 discharges lubricant into pipe 22 which leads to and supplies lubricant to any desired number of lubricant applying devices 23, it being understood that the present invention lends itself to the use of a plurality of such devices as 23 and 30 under ordinary circumstances it is desirable to employ at least four such devices as 23 in connection with each operating mechanism and pump. As the vehicle wheel approaches the lubricant applying device 23 the flange will ride on the upper surface thereof and force member 31 downwardly and inwardly in an arcuate path. This movement brings grooves 40 or other lubricant receiving recesses into position adjacent mouth 42 of lubricant conduit 41 and thereby charges the same with a new supply of lubricant. As the wheel rolls off the top surface of member 31 spring 33 is effective to return the same to the position shown in Figure 3 whereupon the charge of lubricant contained in grooves 40 will be deposited upon flange of the wheel which passes thereover. It will be understood, therefore, that upon each operation of member 31 distributor recesses 40 receive a fresh charge of lubricant which upon return of member 31 to its normal position is deposited upon the flange side face 39 where it may be removed by the next succeeding wheel which presses member 31 out of normal position.

From the foregoing description it is apparent that many modifications of the lubricating device hereinbefore described will present themselves to those skilled in the art which will not depart from the spirit of this invention. It is to be distinctly understood, therefore, that the foregoing description and the accompanying drawing are to be construed as merely illustrative of one embodiment of this invention and not considered in a limitative sense. It is to be understood, therefore, that such modifications and the use of such individual features and sub-combinations of features as do not depart from the spirit of this invention are, although not specifically described herein, contemplated by and within the scope of the appended claims.

Having thus described the invention what is claimed is:

1. A device of the kind described comprising in combination, an operating member arranged for engagement with a passing vehicle part, said

- member disposed for non-uniform movement upon such engagement, a pump operated by said member, and means for maintaining the discharge of said pump uniform.
5. 2. A device of the kind described comprising in combination, an operating member arranged for engagement with a passing vehicle part, said member disposed for non-uniform movement upon successive engagements, and a plunger pump operated by said member and having ports arranged to limit the operative stroke to an intermediate part of the actual plunger stroke.
10. 15. A device of the kind described comprising in combination, an operating member arranged for engagement with a passing vehicle part, a lubricant reservoir, a distributor, a pump for extracting lubricant from said reservoir and forcing the same toward said distributor, and means in said reservoir disposed to prevent channelling of lubricant therein.
15. 20. A device of the kind described comprising in combination, an operating member arranged for engagement with a passing vehicle part, a reservoir disposed to receive heavy lubricant and an agitator in said reservoir operated by said member and arranged to prevent channelling of the lubricant.
25. 30. A device of the kind described comprising in combination, a distributor having a surface normally seated against the flange side face of a rail head and arranged for movement away from the same, and a lubricant supply conduit, said distributor arranged when in normal position to close said conduit.
35. 40. A device of the kind described comprising in combination, a distributor having a lubricant receiving recess normally positioned adjacent the flange side face of a rail head, a normally closed lubricant supply conduit, and means operated by engagement with a passing vehicle part for moving said distributor and connecting the recesses with said conduit.
45. 50. A device of the kind described comprising in combination, a lubricant applying device having a part disposed in the path of the wheel flange of passing vehicles and arranged to be moved thereby, and an arcuate guide for said part.
55. 60. A device of the kind described comprising in combination, a lubricant applying device having a member arranged for engagement with and movement downwardly by a passing vehicle part, and means slidably receiving said member arranged to guide the same laterally inward during such downward movement.
65. 70. A device of the kind described comprising in combination, a lubricant applying device having a member provided with an arcuate guide surface and a surface arranged for engagement with a passing vehicle part, a block shaped for disposition between the flange and head of a rail and having an arcuate surface arranged to receive said member.
75. 80. A device of the kind described comprising in combination, a lubricant applying device having a member provided with an arcuate guide surface and a surface arranged for engagement with a passing vehicle part, a guide for said member arranged for mounting adjacent a rail, and spring means connecting said guide and member and disposed to bias said member into position for engagement with a passing vehicle part.
85. 90. A device of the kind described comprising in combination, an operating member arranged to be engaged and moved laterally by a passing vehicle part, a pump operated thereby, and lubricant applying means arranged for engagement with a passing vehicle part and for movement thereby downwardly and inwardly away from the rail.
95. 100. A device of the kind described comprising in combination, an operating member arranged for engagement with a passing vehicle part, said member disposed for non-uniform movement upon successive engagements, and a plunger pump operated by said member and having an axially extending passageway arranged to be opened to relieve the pressure in the pump cylinder and limit the operative stroke of the pump.
105. 110. A device of the kind described comprising in combination, an operating member arranged for engagement with a passing vehicle part, the amplitude of movement of said member being variable, a plunger pump operated by said member, the length of the stroke of said pump varying in accordance with the amplitude of movement of said member, and means for limiting the discharge of said pump independently of the amplitude of movement of said member.
115. 120. A device of the kind described comprising in combination, a lubricant reservoir, a reciprocable plunger pump having a relatively small passageway communicating with said reservoir and arranged upon movement in one direction to suck lubricant through said passageway, wiping means in said reservoir arranged for movement through the lubricant adjacent said passageway to prevent channelling thereof upon suction by the pump, and means for moving said wiping means during movement of the pump plunger.
125. 130. A device of the kind described comprising, in combination, an operating member arranged to be actuated by a passing vehicle part, a lubricant reservoir, a reciprocable plunger pump having a relatively small passageway communicating with said reservoir and arranged upon movement in one direction to suck lubricant through said passageway, wiping means in said reservoir arranged for movement through the lubricant adjacent said passageway to prevent channelling thereof upon suction by the pump, and connections from said operating member for reciprocating the pump plunger and the wiping means.
135. 140. WILLIAM H. FOSTER.
